UNITED STATES PATENT OFFICE.

LAURA A. FRY, OF CAMP DENNISON, OHIO.

ART OF DECORATING POTTERY-WARE.

SPECIFICATION forming part of Letters Patent No. 399,029, dated March 5, 1889.

Application filed March 16, 1886. Serial No. 196,404. (Specimens.)

To all whom it may concern:

Be it known that I, LAURA A. FRY, of Camp Dennison, in the county of Hamilton and State of Ohio, have invented a new and 5 useful Improvement in the Art of Decorating Pottery-Ware; and I do hereby declare that the following is a full and exact description thereof.

My invention consists in the application to 10 the surface of the ware after the article has received its final shape, and before it is finally glazed or fired, suitable coloring-matter in the form of a cloud or spray, as hereinafter described, whereby a particularly soft, delicate 15 background or shading is produced upon the ware, which may be made to gradually fade or vanish in one or more directions, and to blend from one color to another without any perceptible line of demarkation.

20 It consists, furthermore, in heating the ware when hard or glazed upon the surface and thereafter applying the coloring-matter, in manner as hereinafter described, to the hot surface, and finally firing or glazing the decorated article.

To carry my invention into effect, the coloring-matter is blown upon the surface of the ware—either in its soft state, in the “bisque” state, or on the glaze before firing— 30 in the form of a cloud or an atomized spray or mist, produced by means of any of the usual forms of atomizers which are operated by an air-blast or a steam-blast, or by the lungs of the operator, and which, being well 35 known, need not be herein described. After the ware has thus been decorated the color is fixed by firing the ware in the customary manner. I employ the coloring-matter either in a liquid or semi-liquid form, or in the form 40 of a very dry, almost impalpable, powder, as desired. As the coloring-matter is blown from the tube of the atomizer and carried therefrom in a cloud of fine, almost imperceptible, particles, it may be readily directed 45 upon the article in such manner as may be found best adapted to produce the desired effect, the application being freely made where the color is to be intense, and more delicately made in proportion as the color effect is to be 50 delicate; or otherwise varied as the taste,

skill, or ingenuity of the operator may dictate. A single color may thus be applied to a color ground, or different colors may be applied separately, or, by means of separate atomizing-jets, several colors may be applied 55 simultaneously.

By this process delicate clouding—if “clouding” it may be called—is produced entirely free from outline and possessing a peculiarly delicate “vanish,” and where two colors merge a 60 peculiar softness of blending is secured which may not be otherwise attained. A variety of beautiful and novel effects may also be obtained which it is not necessary herein to describe.

The coloring-matter and the glazing material for the clay-ware may be mixed together and applied to the article by my process, or the coloring-matter may be applied as above described, and the glaze thereafter applied by 70 the usual process of dipping and firing.

Where the clay-ware to be colored or decorated has been once fired, and is not therefore sufficiently absorbent, I heat the same before blowing the color thereon, the effect of 75 the heat of the article being to cause the liquid coloring-matter to quickly dry without marring the effects which are sought in its application.

I am aware that coloring-matter in a liquid 80 state has heretofore been applied to the glazed surfaces of china-ware by sprinkling or spattering the same thereon with the aid of a comb and brush, the comb being passed over the brush dipped in the coloring-matter in 85 such manner as to cause the latter to fly off in fine independent drops or particles, this process being technically known as “spatter-work,” and I make no claim thereto.

My improved process differs from spatter-work in that, instead of being spattered in small independent drops, the color is laid upon the ware in a cloud or sheet of almost imperceptible spray or mist, producing very different effects, and such have hitherto been 95 unknown.

I claim as my invention—

1. The improvement in the art of decorating articles of clay-ware, which consists in blowing an atomized spray or cloud of coloring- 100

matter upon the surface thereof, and thereafter fixing the same by firing, substantially in manner as described.

2. The improvement in the art of decorating clay-ware, which consists in heating the surface and blowing upon the heated surface an atomized spray or cloud of coloring-matter, and thereafter fixing the same by firing, substantially in manner as described.

In testimony whereof I have signed my name to this specification in the presence of two subscribing witnesses.

LAURA A. FRY.
